TOY PISTOL

Morris Eigen, North Bergen, N. J.

Application November 9, 1951, Serial No. 17,344

Term of patent 3½ years

(Cl. D34—15)

To all whom it may concern:

Be it known that I, Morris Eigen, a citizen of the United States, residing at the city of North Bergen, county of Hudson, and State of New Jersey, have invented a new, original, and ornamental Design for a Toy Pistol, of which the following is a specification, reference being had to the accompanying drawing, forming part thereof, wherein

Fig. 1 is a perspective view of a toy pistol, showing my new design;

Fig. 2 is a back perspective view of the other side of the toy pistol.

I claim:

The ornamental design for a toy pistol, substantially as shown.

MORRIS EIGEN.
